ELECTRIC CIRCUIT INTERRUPTER

David C. Prince, Swarthmore, Pa., assignor to
General Electric Company, a corporation of
New York

Application December 24, 1935, Serial No. 56,050

4 Claims. (Cl. 200—120)

My invention relates to electric circuit interrupters, more particularly to interrupters of the fluid blast type wherein pressure generated by arcing at one point in the circuit is utilized to 5 create a fluid blast for interrupting arcing at another point in the circuit.

In certain types of air-break circuit interrupters, such as expulsion fuses for example, turbulence of the highly heated gases, vapors and 10 arc products exhausting through the arc is mainly relied upon for the interrupting action. That is, notwithstanding the presence of gas ionized by arcing mixed with un-ionized gas, the turbulence of the high velocity exhaust is such that 15 during the brief interval of current reversal and before the recovery of voltage across the gap, the continuous stream of arc products is so broken up by insulating medium that the arc cannot reestablish. However, this process is largely fortuitous and depends upon extremely 20 turbulent mixing of the un-ionized, or insulating, and ionized gases, since the ionized gases when at pressures of the order of atmospheric 25 pressure and higher deionize quite slowly, retaining a considerable portion of their conductivity after several cycles at commercial power frequencies.

The principal object of my invention is the provision of an improved circuit interrupter of 30 the aforesaid fluid blast or expulsion type wherein the effect of the highly heated ionized gas on the arc to be interrupted is minimized in a positive and predetermined manner. In accordance with my invention in a structural embodiment 35 thereof, a so-called "dead" region is provided between the pressure generating arc and the portion of the arc subject to the fluid blast, the arrangement preferably being such that the un-ionized gas stored in the dead region is substantially entirely expelled and used in the fluid blast 40 and the ionized gas subsequently is necessarily thoroughly mixed with and cooled by any un-ionized gas remaining in said region and also cooled by the structure defining said dead or storage region.

My invention will be more fully set forth in 45 the following description referring to the accompanying drawing, and the features of novelty which characterize my invention will be pointed out with particularity in the claims annexed to and forming a part of this specification.

Referring to the drawing, Fig. 1 is a view, mainly in section, of an electric fuse of the 50 expulsion type embodying my invention; Fig. 2 is a sectional view of the fuse taken along the line

2—2 of Fig. 1, and Fig. 3 is a view, mainly in section, of an electric circuit breaker likewise embodying my invention.

The electric circuit interrupter illustrated by Fig. 1 constitutes a fuse of the well known expulsion type comprising a mechanically strong cylindrical insulating casing 1, end terminals 2 and 3, and a fusible element 4 extending through the cylinder 1 and electrically interconnecting the fuse terminals. The terminals are composed of a suitable conducting material, such as copper, the terminal 2 being in the form of a cap closing one end of the cylinder 1 and the terminal 3 being in the form of a ring at the open end of the cylinder. The fusible element 4, which is 10 electrically connected in any suitable manner to the terminals, is preferably provided with a reduced section or equivalent thereof at 4' for insuring initial blowing of the fuse in response to predetermined current in that region of the 15 casing.

In the apparatus so far described, the circuit interrupter functions in the conventional manner, that is by blowing of the fuse within the cylinder 1 accompanied by violent expulsion of 20 the gas, metallic vapor and arc products through the open end of the cylinder.

For the purpose of forming a so-called dead region adapted to serve as a gas reservoir between the pressure generating arc, that is, the portion 25 of the arc within the closed or pressure confining part of the fuse casing, and a portion of the arc in another part of said casing subject to the gas blast, there is provided a sectionalized structure 6 positioned, in the present instance, within the cylinder 1 between the terminals 2 and 3 and between the weakened portion of fuse element 4' and the open end of the cylinder.

The structure 6 comprises a longitudinally positioned conducting arc member 7 to which are 30 secured in radial position a plurality of fin-like members 8, as best illustrated by Fig. 2. The fin-like members 8, which in the present instance are composed of conducting material, but which may, if desired, be composed of insulating material, are of such length that they define gas spaces of appreciable volume which communicate respectively with the regions of both portions so that the flow of gas through the fuse cylinder is not appreciably restricted.

It will, therefore, be apparent that the specific 35 design, including the dimensions and proportions of the intermediate structure 6, may be varied in accordance with the desired interrupting capacity and characteristics of the fuse.

In operation, excessive or predetermined current in the circuit in which the fuse is connected causes the fusible element to blow at 4' within the confined portion of the fuse casing, with the result that high instantaneous arc pressure is set up within that part of the casing. This pressure not only causes violent ejection of the remainder of the fusible element from the fuse cylinder, but also a considerable volume of gas, metallic vapor and arc products at high velocity. However, upon initial blowing of the fusible element, the arc tends to strike between the fuse terminals and the adjacent ends of the arc member 7, thereby separating the arc into two sections and forming a so-called dead region unaffected by the arc at the conducting structure 6. Due to the explosive action of the pressure generating arc between 2 and 7, the arc within the open end of the fuse casing, that is, between the terminal 3 and the adjacent end of the arc member 7, is subjected to a fluid blast composed initially, at least, mainly of the cool air or gas originally within the dead region defined by the fins 8. Accordingly, the arc is subjected to a blast of deionized air which is substantially non-conducting and has high dielectric strength as compared with ionized gas. For normal operation, the arc not only would be interrupted by this blast but the high dielectric strength of the cooled gas medium would prevent reestablishment of the arc when the full line voltage appears across the fuse terminals.

The structure 6 furthermore functions to cool and thoroughly mix the ionized gas blown from the closed or pressure generating end of the fuse casing with un-ionized gas in the dead region prior to passage of this part of the fluid blast through the arc gap in the open end of the tube. It will be noted that the effective cooling area of the structure defining the dead space is large as compared with the cross-sectional area of the casing. Accordingly, the effect of the hot ionized gas from the region of the pressure generating arc is minimized in a positive and predetermined manner prior to its passage through the gap subject to the interrupting blast.

Fig. 3 illustrates a circuit breaker generally similar in principle to the fuse above described. In this case, the switch casing 9 likewise comprises an insulating cylinder open at one end and closed by circuit terminal cap 10 at its other end. Relatively movable contact structure is disposed within the switch casing comprising, in the present instance, a fixed contact 11 connected to the terminal 10, an intermediate contact rod 12 guided for reciprocal longitudinal movement within the switch casing, and a movable contact 13 to which is connected an operating rod 14. The contacts 11, 12 and 13 are generally in alignment, the intermediate contact 12 engaging at its opposite ends the fixed contact 11 and the movable contact 13, respectively, and the movable contact 13 being electrically connected through the conducting operating rod 14 to the other terminal 15 of the breaker. The contact 12, which makes butt contact with fixed contact 11, engages the movable contact 13 at a central opening 13' generally in the manner of a needle valve, so that separation of the contacts 12 and 13 provides an opening through the contact 13 for exhaust of fluid through the open end of the switch casing 9.

As illustrated, the breaker is in the closed circuit position and is held in such position by latch 16 operatively related to a tripping solenoid 17.

As in the previous instance, a dead or unaffected region is formed between the pressure generating arc, which is formed between the contacts 11 and 12, and a portion of the arc subject to the fluid blast, which is formed between the contacts 12 and 13, the arrangement comprising a plurality of fins 18 secured to and radially positioned with respect to the intermediate contact 12. The contact 12 includes an outer sleeve 19 which surrounds the fins 18 and is slidable within limits within the casing 9. A compression spring 20 tends to bias the sleeve 19 and hence the contact 12 away from fixed contact 11.

In operation, when the tripping solenoid is actuated to release the latch 16, suitable operating means, such as springs (not shown), causes opening movement of the contact 13. By reason of the spring 20, there is a limited following engagement between the contacts 12 and 13 and immediate initial separation of the contacts 11 and 12, resulting in formation of the pressure generating arc within the closed or pressure confining part of the switch casing. When the sleeve, however, reaches the shoulder 9' within the switch casing, following movement of the contact 12 is checked and separation of the contacts 12 and 13 draws another arc at that point.

The pressure initially generated is, therefore, effective immediately to cause a blast of gas through the central opening in the contact 13 to exhaust from the switch casing and hence through the arc between the contacts 12 and 13. Accordingly, the un-ionized gas within the dead region defined by the fins 18 not only functions in the manner above described to provide a substantially un-ionized gas blast through the arc between the contacts 12 and 13, but also prevents reestablishment of arcing between these contacts in the manner described in connection with Fig. 1.

The application of my invention to a circuit breaker is obviously not limited to the specific construction shown, and, by way of example, the pressure generating arc could if desired be formed by a fusible element, the pressure being utilized to open the contact 13 as well as to create the interrupting blast.

It should be understood that my invention is not limited to specific details of construction and arrangement thereof herein illustrated, and that changes and modifications may occur to one skilled in the art without departing from the spirit of my invention.

What I claim as new and desire to secure by Letters Patent of the United States is:

1. An electric circuit interrupter of the gas blast type comprising a pressure-confining casing, circuit controlling means including spaced terminals and interposed conducting arc means arranged to form in said casing two breaks in series in accordance with the circuit interrupting operation, one of said breaks being adjacent to an exhaust opening of said casing and the other break being more remotely positioned in said casing so as to form a pressure-generating arc, and means interposed between said breaks comprising a sectionalized gas-cooling structure having a large effective surface area as compared with the cross-sectional area of said casing, said structure forming a plurality of passages in communication with the regions of said breaks. 70

2. An electric circuit interrupter of the gas expulsion type comprising a pressure-confining chamber, circuit-controlling means including spaced terminals and interposed conducting arc means arranged to form two breaks in series 75

- in accordance with the circuit-interrupting operation, one of said breaks being adjacent an exhaust opening of said chamber, and the other break being more remotely positioned within said chamber so as to form a pressure-generating arc, and gas-cooling structure having a large effective surface area as compared with the cross-sectional area of said chamber interposed between said breaks for defining a sectionalized (as contrasted with a substantially open) space, said sectionalized space also serving as a reservoir for cool un-ionized gas and communicating with the regions of both said breaks whereby an initial charge of cool gas from said sectionalized space is projected across the arc at said exhaust opening by the pressure generated at the other arc, and the highly heated arc gases from said pressure-generating arc are subsequently effectively cooled in said structure prior to passage through the break at said exhaust opening.
3. An electric circuit interrupter of the gas expulsion type comprising a casing, circuit terminals associated with said casing, a fusible element disposed within said casing and adapted initially to blow at a point within an enclosed part of said casing, said casing having a pressure relief opening at another part thereof, means positioned intermediate said terminals for segregating arcing at the terminal adjacent said point of initial blowing and that adjacent to said relief opening, and gas-cooling structure disposed within said casing intermediate the regions of said arcing, said cooling structure having a large effective surface area as compared with the cross-sectional area of said casing and defining a plurality of passages communicating with said regions, said passages also serving as a reservoir for cool un-ionized gas whereby the arc pressure generated within said casing at said point of initial blowing causes expulsion of un-ionized gas from said passages through the other arc and the heated arc gases from said region of initial blowing are cooled prior to expulsion through said other arc.
4. A circuit breaker of the gas expulsion type comprising a pressure-confining chamber, relatively movable contacts arranged to form two breaks in series within said chamber in accordance with the circuit-opening operation, one of said breaks being adjacent to an exhaust opening of said chamber, and the other break being remotely positioned within said chamber so as to form a pressure-generating arc, and gas-cooling structure having a large effective surface area as compared with the cross-sectional area of said chamber interposed between said breaks defining a sectionalized (as contrasted with a substantially open) space, said sectionalized space serving also as a reservoir for cool un-ionized gas and communicating with both regions of arcing whereby an initial charge of cool gas from said sectionalized space is projected across the arc at said exhaust opening by the pressure generated at the other arc, and the heated arc gases from said pressure-generating arc are subsequently effectively cooled in said structure prior to passage through the break at said exhaust opening.
